ATTORNEYS.

UNITED STATES PATENT OFFICE.

EDWARD H. WHITNEY, OF SUPERIOR, WISCONSIN.

PORTABLE TRUSS.

1,190,834.

Specification of Letters Patent. Patented July 11, 1916.

Application filed May 6, 1915. Serial No. 26,301.

To all whom it may concern:

Be it known that I, EDWARD H. WHITNEY, a citizen of the United States, residing at Superior, in the county of Douglas and 5 State of Wisconsin, have invented certain new and useful Improvements in Portable Trusses, of which the following is a specification, reference being had therein to the accompanying drawing.

10 My invention relates to improvements in portable trusses, and especially to a portable truss which may become available for various jobs of lifting and suspending various articles.

15 The primary object of the invention is to provide a simple and readily adjustable device of this character to facilitate in the unloading of automobiles from railway box cars.

20 Another object is to construct the device in such a manner that the maximum strength may be afforded from the least amount of material, and thus provide an exceptionally convenient supporting truss.

25 In the accompanying drawings, forming a part of this application; Figure 1 is a side elevation of my improved truss in an operative position. Fig. 2 is a front view of one of the bifurcated ends of one of the struts 30 of the truss. Fig. 3 is a cross sectional view through a box car, illustrating the application of the device in removing an automobile therefrom.

Referring now to the drawings in which 35 like reference numerals designate similar parts throughout the several figures, 1 represents the horizontal member, or tie-rod, of the truss, which is preferably formed of a piece of metal pipe or tubing, this being 40 of a length somewhat less than the distance between the side walls of an ordinary box car. A screw threaded bolt 2, having a nut 3 mounted thereupon, is designed to freely fit within each end of the pipe, there being 45 one such bolt and nut for each end of the pipe 1, and when positioned within the pipe, as illustrated in the drawings, it is evident that the over-all distance between the protruding ends thereof, may be varied at will 50 by turning one way or the other the nuts 3-3, the object of which will appear later, the nuts 3-3 being considerably larger in diameter than the pipe. Braces or struts 4 and 5 are pivotally attached at their bifurcated ends to the rod 1, by means of a through pin 6, such points of attachment be-

ing inward, somewhat, from the ends of the rod 1, to present the most desirable inclination of the strut when in operation, the same points of attachment being that from whence the load is suspended from the truss. A clevis 7 is suspended from each of the pins 6, thus forming a suitable engaging means for block and tackle. The bifurcated ends of the struts 4 and 5 are arched slightly 65 inward to provide for their snugly folding inwardly against the rod 1 when the truss is being transported from place to place. The struts 4 and 5 are of metal practically the same size as the rod 1, each having telescopically mounted therein a smaller and somewhat shorter pipe 8, having a plurality of through transverse holes 9 therein, which may be made to register with similar through holes 10 within the struts 4 and 5, 75 as clearly seen in the drawings. By this arrangement the struts may be extended or shortened to suit circumstances, there being one or more bolts 11 employed in engaging the struts and pipes through the holes 80 therein, and at the predetermined relative position desired.

Within the outwardly extending end of each of the pipes 8 is loosely fitted the screw threaded bolt 12, having the nut 13 mounted thereupon, by which the length of the bolt 85 protruding beyond the pipe 8 may be readily varied, which is identical with the adjustment of the bolts 2-2 in the ends of the pipe 1.

90 In the application of the device to unloading automobiles from a box car, the lowermost tier of automobiles having been removed first, the truss is placed up close to the ceiling of the car, just above one end 95 of the automobile to be lifted, and the bolts 2-2 extended longitudinally by turning the nuts 3-3 in the proper direction, until the ends of the bolts are forced tightly against the frame 14-14 of the car body, the nuts 100 3-3 impinging against the ends of the rod 1 as is understood. This having been accomplished the telescopic members of the struts 4 and 5 are adjusted to approximately the proper distance to meet the most convenient 105 bearings 15-15 upon the sides of the car, the bolts 12-12 placed within the pipes 8-8, and the proper final adjustment accomplished by turning the nuts 13-13, when the truss will be firmly fixed in place ready 110 to lift. Suitable lifting tackle, such as chain blocks 16-16 are then hooked into the elev-

ises 7—7 and attached to the automobile as desired, preferably to the ends of the springs, as illustrated. A duplicate of this arrangement may be employed at the opposite end of the automobile to be removed, or in some cases it may be more convenient to use a single block and tackle suspended from the ceiling of the car, as the end of the automobile nearest the door in the car is usually more accessible to single tackle. When the suspending tackle is thus attached, tension is applied thereto, until the weight of the automobile is taken up, at which time the temporary staging 17 is removed and the automobile lowered to the floor of the car.

From the foregoing it is evident that I have produced a simple and practical truss which is especially well fitted for convenience in unloading automobiles from box cars.

Having thus described my invention, what I claim as new and desire to secure by Letters Patent is,

1. A device of the character described, comprising a tie-rod, means adjacent its ends and coöperating therewith for chang-

ing the length thereof, longitudinally adjustable struts pivotally attached to the rod, and means for suspending the load from the tie-rod.

2. A device of the character described, comprising a tie-rod, means adjacent its ends and coöperating therewith for changing the length thereof, a longitudinally adjustable strut pivotally attached to the tie-rod adjacent each end thereof, means for attaching hoisting tackle at the pivotal points of contact of the struts and tie-rod.

3. A device of the character described, comprising a tie-rod, means carried by the rod and coöperating therewith for changing the length thereof, longitudinally adjustable struts pivotally attached to the rod and means for suspending a load from the tie-rod.

In testimony whereof I hereunto affix my signature in the presence of two witnesses.

EDWARD H. WHITNEY.
